BEARING CAP OR THE LIKE

James W. Bradbury, Middletown, Ohio, assignor to Forward Corporation, Middletown, Ohio, a corporation of Ohio

Filed May 31, 1963, Ser. No. 75,137

Term of patent 3½ years

(Cl. D46—1)

FIG. 1 is a front perspective view of a bearing cap or the like showing my new design.

FIG. 2 is a front elevational view thereof.

FIG. 3 is a plan view taken from the left of FIG. 2.

FIG. 4 is a plan view taken from the top of FIG. 2.

FIG. 5 is a sectional view taken on line 5—5 of FIG. 2.

FIG. 6 is a plan view taken from the rear of FIG. 2.

I claim:

The ornamental design for a bearing cap or the like, as shown.
